ROBERT FLEMING ARNOTT, OF MONTCLAIR, NEW JERSEY.

BALANCED BALL.

Original application filed January 13, 1921, Serial No. 437,079. Divided and this application filed May 3, 1921, Serial No. 466,605. Renewed October 20, 1925.

Some balls, particularly those made from various parts, such as golf balls, are not evenly balanced, by reason of unevenness in assembling the parts, which may occur because of some eccentricity at the surface, excess weight at some part, or for other causes. Such balls are particularly disadvantageous when used for playing games, such as golf balls. Golf balls are usually made with an inner core or "center" of suitable material, a winding on the core of relatively wide bands of rubber, and an outer cover or shell. Said balls are sometimes normally heavier on one side than the other causing unevenness in playing, the balls tending to deviate from a straight line or course when hit, especially when hit lightly to roll on a putting green.

The object of my invention is to provide balls that will be properly balanced so that the balls will not tend to deviate from a straight course when hit.

In carrying out my invention I ascertain which is the lighter side of the ball, if any, and I insert within the ball at the lighter side a material, such as fluid metal, having sufficient weight to cause that side of the ball to substantially correspond in weight to the opposite or heavier side and thus balance the ball. In the case of balls having inner wound strips or bands, such as golf balls, I insert said weighty material through the cover into the interstices between the windings on the lighter sides to increase the weight on that side proportional to the amount the ball is out of balance.

In the accompanying drawings I have illustrated a conventional form of golf ball embodying my invention, wherein

Figure 1 is a partly broken side view of the ball showing the balancing material under the cover; Fig. 2 is an exaggerated fragmentary view of part of the ball, and Fig. 3 is a detail plan view.

The golf ball 1 illustrated comprises an inner core or "center" 2, a winding 3 thereon of relatively wide rubber bands, an outer winding 4 of narrow rubber bands, and an outer shell or cover 5 securely enclosing the core and winding. The ball described is of the conventional golf ball construction. The bands 4 are shown wound in irregular or criss-cross fashion providing interstices between the windings. At 6 is the loading material inserted through the shell or cover

into the windings 4. Said material may be fluid metal, such as a suitable metal or alloy, or amalgam or colloidal metal. I preferably employ a suitable metal alloy that will flow at a relatively low temperature, having a relatively low melting point, which will quickly harden or set when cooled, but do not restrict myself to this. The loading material or metal enters the interstices between the windings of the bands 4 beneath the cover to remain in place under the impact of blows upon the ball. The cover retains the loading material 6 within the ball.

The ball may be floated in a suitable bath of fluid to ascertain its lighter side. If the ball is normally out of balance its lighter side will extend upwardly, and a needle may be pushed through the cover 5 at such lighter side whereupon the loading material of requisite amount to balance the ball will be forced from the needle into the inner material of the ball, after which the needle will be withdrawn. The fluid material will interspace in the interstices of the winding and when set will remain in the interstices of the bands 4. The hole pierced in the cover by the needle will close by expansion of the cover, or may be plugged by any desired material.

The material 6 may be inserted or injected into the ball by any desired means, such as through a hollow instrument or needle, preferably having a sharp point and a side outlet. Such a needle is indicated in dotted lines at 7. The material may be forced into the ball from needle 7 by any suitable means, such as a pump, after the needle has pierced the cover 5, and preferably has entered the winding 4 to a suitable depth.

A method and means for balancing the balls and inserting the loading material in the balls I have disclosed in my application filed Jan. 13, 1921, Serial No. 437,079, of which this application is a division.

My improved balls will be found to be of advantage where it is desired to have the balls as nearly evenly balanced as possible, particularly so with golf balls, which have a tendency to run off the desired course or deviate from a straight line, particularly in putting such balls on a putting green, since normally unbalanced balls when putted are liable to spoil the intended put.

My invention is not limited to use with the particular ball illustrated, as balls of other

constructions may be balanced as set forth herein.

Having now described my invention what I claim is:—

- 5 1. A balanced ball comprising an outer continuous cover, inner windings, and a core, said ball being provided with material within said windings wholly without the core to balance the ball.
- 10 2. A balanced ball comprising an outer continuous cover, inner material having interstices, and balancing material in the interstices on one side of the ball.

3. A balanced ball comprising an outer continuous cover, inner windings having interstices, and metal interspersed in the interstices on one side of the ball. 15

4. A balanced ball comprising an outer continuous cover, inner windings having interstices, and metal solidified in said interstices within the ball. 20

Signed at New York city, in the county of New York, and State of New York, this 2nd day of May, A. D. 1921.

ROBERT FLEMING ARNOTT.
